HEATING PROCESS AND APPARATUS

Anthony E. Hassler, Ridley Park, and Hugh W. Field, Glen Mills, Pa., assignors to The Atlantic Refining Company, Philadelphia, Pa., a corporation of Pennsylvania

Application February 9, 1934, Serial No. 710,476

5 Claims. (Cl. 196—116)

The present invention relates to a heat distributor for use in furnaces in which the tubes through which liquid to be heated is passed, are disposed vertically and in concentric relation to 5 the source of heat.

Our invention is particularly applicable to furnaces of the de Florez type in which the liquid entering the tube system passes alternately upwardly and downwardly through the adjacent 10 tubes parallel to the flow of combustion gases until it has traversed the entire circle of the tubes and is withdrawn therefrom at a point adjacent to point of introduction. Such furnaces are used for heating hydrocarbon oils, particularly 15 petroleum oils in the production of gasoline from heavier hydrocarbons by thermal decomposition or cracking. In cracking oils in furnaces of this type it is desirable to maintain a careful regulation of the heat input to the oil tubes in 20 various sections of the furnace but this is not possible in the ordinary type of construction. We have found that the heat input may be controlled, and by so doing we have been able to increase the cracking performance of the furnace by 25 bringing the oil to the cracking temperature more rapidly, thus increasing the amount of cracking per cycle on the oil passing through the furnace since the oil is at the cracking temperature for a longer portion of its travel through the tubes.

30 Furnaces of the de Florez type are generally constructed with a number of liquid or gaseous fuel burners, usually 3 or 5 located either at the top or the bottom of the furnace and concentric with respect to the tubes. Heretofore, the conventional method of controlling the temperature 35 in the various tube sections has been to regulate the quantity of fuel supplied to each of the several burners. In attempting this control on the furnaces of conventional construction, we have found it extremely difficult to obtain the desired 40 degree of heat distribution.

For example, the furnace under consideration 45 may contain a series of 100 vertical tubes arranged within the periphery of the furnace walls and surrounding a set of 5 burners. The series of tubes may be arbitrarily divided, for example, into 5 sections of 20 tubes each. In the event that it is found desirable to increase the heat input into the first 20 tubes, the fuel flow to the 50 burner adjacent these tubes would be increased. However, due to the fact that the distance from this burner to the nearest tube is not markedly less than the distance from the same burner to the tubes on the opposite side of the furnace, 55 a considerable portion of the increased heat is

absorbed by tubes other than those to which it is desired to supply additional heat. As a result it is impossible to maintain a substantial variation of heat input to the several sets of tubes.

In order to overcome this difficulty and to effect the desired control of heat input to the various tube sections in the furnace, we provide a heat deflecting surface adjacent each of the several burners so that the radiant heat therefrom may be directed to the proper tube section. The 10 heat deflecting surface may be constructed of refractory material, such as fire brick or heat resistant alloy steels, and of such height that the radiant heat from each burner is reflected to the tubes nearest that burner, while the major 15 portion of the radiant heat is prevented from passing across the furnace and affecting the other tubes. The deflecting surface is preferably of such height that the entire length of the tube section which it is desired to hide from the flame 20 from any particular burner will be protected. If, for any reason, it may be desirable to heat the upper portion of the tube section to a greater extent than the lower portion, the height of the deflecting surface may be reduced so that the 25 upper portion of the tube section is exposed to radiation from any burner in addition to the one adjacent the particular tube section. Or, if it is desired that an increased amount of the radiant heat from the several burners be reflected to the upper portion of the tube sections, the 30 deflector surfaces may be sloped to form, for example, a polygonal truncated pyramid.

For a further understanding of our invention, reference is made to the accompanying drawings, Fig. 1 of which illustrates one form of apparatus suitable for effecting heat control.

The furnace comprises a vertical metal shell 1 supported by members 2 and lined with a heat insulating material 3 such as, for example, insulating bricks. The insulating material 3 is protected from combustion gases by a facing of refractory brick 4, i. e., fire brick. Disposed within the surface is a series of tubes 5 connected by means of headers 6, said tubes being concentrically arranged with respect to the source of heat. The furnace is provided with a flue 7 within which is disposed a series of tubes 8 which function as a preheating section for the liquid to be introduced into the tubes 5. The furnace is heated by means of a plurality of burners whose outlets may be represented by the orifices 9. Fuel, in the form of oil or gas, is supplied to the burners thru valve-controlled pipes 10 and the air necessary to support combustion is drawn into 40 45 50 55 60 65 70 75 80 85 90 95 100 105 110 115 the wind-box 11 from ports provided in the bottom of said box. The mixture of air and fuel is injected into the furnace thru the orifices 9, and the resulting combustion supplies heat to the tubes 5.

5 In order to control the distribution of heat in any desired section of the furnace tubes, a heat deflecting surface 12 is disposed adjacent to each burner orifice. This surface provides a means 10 whereby the radiant heat from each burner is concentrated in that section of the furnace nearest the deflecting surface. The heat deflector is preferably constructed in such a manner that the point of maximum heat of the burner flame is 15 approximately midway of the length of the deflecting surface. The upper portion of the deflector thus shields the tube section on the opposite side of the furnace from the radiant heat of the burner adjacent the deflecting surface. The deflector is preferably constructed of 20 refractory material, with a deflecting surface for each burner. Each surface may be further defined by means of fins 13, extending either partially or totally the vertical length of the deflecting surface. Furthermore, the fins 13 may be 25 extended horizontally in the direction of the conical refractory wall forming the base of the furnace, thereby more closely confining the heat from each of the several burners to their respective sets of tubes.

Referring to Figs. 2 and 3 of the drawings, which respectively illustrate diagrammatically horizontal, sectional views of a furnace, with and without the installation of our heat deflecting device. Like parts are identically numbered and correspond substantially to the parts shown in Fig. 1 of the drawings.

In Figs. 2 and 3, the direct radiation of heat from a burner 9 is represented by the solid lines drawn radially from the heat source. Those rays impinging upon the heat absorbing tubes 5 are considered to be totally absorbed, while rays impinging upon the refractory furnace walls 4 or heat-deflecting surfaces 12 and 13 are reflected to a substantial extent, as shown by the broken lines. For simplicity, the once reflected rays only are shown; actually reflection may occur 3 or 4 or more times before absorption is effected.

50 The heat concentrating effect of the deflector is clearly illustrated in Fig. 2, substantially all of the rays being confined to that section of the furnace adjacent the burner and deflector wall under consideration. At the same time the deflector functions to prevent heat from the remaining burners from impinging to substantial extent upon the furnace tube sections other than those adjacent said remaining burners. By maintaining a greater heat input in that section of the 55 furnace adjacent the fluid inlet, such fluid may be brought rapidly to the desired temperature shortly after its introduction into the tube system, without increasing to an undesirable extent the heat input to the other furnace tube sections. 60 Thus, our heat deflector functions to concentrate the heat in any desired section of the furnace, and simultaneously shields the non-adjacent sections to substantial extent.

70 Fig. 3 shows a furnace in which no heat deflector has been installed, and it will be seen that since there is no means for directing the heat input to any particular section of the furnace, an increase in heat input from any burner will be distributed thruout the furnace and it is there-

fore impossible to regulate the distribution to give satisfactory or desired results.

It will be seen that the increased firing of one or more of the burners will result in an increase in heat input to the furnace, and by the employment of our deflecting device the resulting heat may be directed to the desired tube section of the furnace.

As an example of the improved results obtained by means of our invention, in cracking an overhead fraction from the Texas crude in a furnace having a plurality of vertical tubes arranged in circular fashion around the burners without the employment of the heat deflecting device, 15 68% of the path of flow was traversed by the oil before it attained a temperature of 950° F.; when a five faced deflector was installed in accordance with our invention and the burners adjusted to give the maximum heat in the early heating stages the oil reached 950° F. when it had traversed 20 45% of the path and, since it was at the cracking temperature for a longer portion of its path through the furnace, the quantity of motor fuel produced per day was increased 36% over the 25 quantity produced by the same still without employing our invention.

While we have illustrated our invention showing a pentagonal form of heat deflector, we do not intend to limit ourselves thereto but consider within the scope of our invention a deflector of 30 any shape adapted to shield one or more tube sections. Furthermore, while our invention is described with particular reference to a furnace adapted for heating hydrocarbon oils, it is to be understood that our heat deflector is applicable 35 to any furnace equipped with vertical tubes arranged in a circular manner, regardless of the nature of the fluid which is to be heated. For example, it may be used in apparatus for the generation of steam. It is further to be understood that the fin type structure built out from each deflecting surface, while generally of material advantage, may be dispensed with if desired.

What we claim is:

1. In a furnace having a plurality of vertical 45 heat absorbing tubes disposed therein about the periphery thereof, a multi-faced, relatively non-absorbing heat deflector positioned centrally of said tubes, fins of relatively non-heat absorbing material extending radially from the vertical 50 boundaries of the deflector faces, and a burner adjacent each heat deflecting face, whereby radiant heat from each burner is directed to the tubes immediately adjacent each deflecting face.

2. A method for heating hydrocarbon fluids 55 which comprises passing the fluid to be heated about the periphery of a heating zone in a series of relatively short alternate upward and downward paths, supplying heat from a plurality of sources located centrally of said heating zone, 60 varying the supply of heat to the fluid as it passes thru said path by maintaining a differential between the intensities of heat at the several sources, and causing heat from each of said sources to impinge substantially uniformly upon that portion of said path adjacent thereto, while preventing heat from any of said sources from impinging to substantial extent upon any portion 65 of the path other than that adjacent thereto.

3. A method for heating hydrocarbon fluids 70 which comprises passing the fluid to be heated about the periphery of a heating zone in a series of relatively short alternate upward and downward paths, supplying heat from a plurality of sources located centrally of said heating zone, 75

varying the supply of heat to the fluid as it passes thru said path by maintaining the intensity of heat at one of said sources greater than that at another, and causing heat from each of said sources to impinge substantially uniformly upon that portion of said path adjacent thereto, while preventing heat from any of said sources from impinging to substantial extent upon any portion of the path other than that adjacent thereto.

4. In the art of cracking petroleum, the steps which comprise passing the oil in a generally circular path about the periphery of a heating zone in a series of relatively short alternate 15 upward and downward paths parallel to the flow of combustion products passing from a plurality of sources of combustion arranged centrally of the heating zone and rapidly bringing the oil to the cracking temperature by maintaining a higher intensity of heat in at least one source 20 of heat adjacent the point of introduction of oil to the circular path than is maintained in the sources of heat adjacent the point of withdrawal of the oil from the circular path and 25 shielding the last-named portion of the circu-

lar path from the heat evolved at the source of heat adjacent the first-named portion of the circular path.

5. In the art of cracking petroleum, the steps which comprise passing the oil in a generally 5 circular path about the periphery of a heating zone in a series of relatively short alternate upward and downward paths parallel to the flow of combustion products passing from a plurality of sources of combustion arranged centrally of 10 the heating zone and rapidly bringing the oil to the cracking temperature by maintaining a higher intensity of heat in at least one source of heat adjacent the point of introduction of oil to the circular path than is maintained in the 15 sources of heat adjacent the point of withdrawal of the oil from the circular path and shielding the last-named portion of the circular path from the heat evolved at the source of heat adjacent the first-named portion of the circular 20 path and supplying sufficient heat to the oil from the remaining sources of heat to maintain it at least at the cracking temperature.
